UNITED STATES PATENT OFFICE

155,236

DESIGN FOR A SOFA

Abe L. Rothstein, Newton, Mass.

Application October 20, 1947, Serial No. 142,017

Term of patent 7 years

(Cl. D15—11)

To all whom it may concern:

Be it known that I, Abe L. Rothstein, a citizen of the United States, residing at Newton, in the county of Middlesex and State of Massachusetts, have invented a new, original, and ornamental Design for a Sofa, of which the following is a specification, reference being had to the accompanying drawing, forming part thereof.

The flower design is continuous in the upholstering as shown in the drawing figures.

The appearance of the end of the sofa not shown by the drawing figures is substantially the same as the end shown.

The rear of the sofa which is not shown by the drawing figures is conventional.

I claim:

The ornamental design for a sofa, as shown and described.

ABE L. ROTHSTEIN.
